UNITED STATES PATENT OFFICE.

GUS MAJOR KAISER, OF NEW YORK, N. Y.

SAFETY-RAZOR.

1,087,778.

Specification of Letters Patent. Patented Feb. 17, 1914.

Application filed November 26, 1913. Serial No. 803,263.

To all whom it may concern:

Be it known that I, GUS MAJOR KAISER, a citizen of the United States, residing at New York city, in the county of New York and State of New York, have invented new and useful Improvements in Safety-Razors, of which the following is a specification.

The general object of this invention is to refine the construction of safety razors, in point of promoting the efficiency of the same and in cheapness of manufacture. And to these ends the invention resides in a flat, relatively rigid blade and a resilient shield adapted to be adjusted in relation to the edges of the blade.

Other objects will appear and be better understood from that embodiment of my invention of which the following is a specification, reference being had to the accompanying drawings forming part hereof, in which:

Figure 1 is a perspective view of my improved razor. Fig. 2 is a side view of the razor partly in elevation and partly in section. Fig. 3 is a dissected perspective view of the elements forming the razor.

The razor, as shown in the drawings, consists of the holder 5 and the blade 6. The holder 5 is formed of a plurality of members 30 which include the handle 7, the guard 8 and the blade retaining member 9.

The blade 6 used in my improved razor is formed from a flat and relatively rigid sheet of razor-steel, and while it is of sufficient thinness to admit of a minimum expense in manufacture, it is substantially rigid for all purposes of shaving. In order that it may be especially adapted to be used in my improved razor-holder, which will be hereinafter fully described, a centrally disposed perforation 10 is provided in the blade; and so that the life of the blade may be doubled, the usual double shaving-edge 11—11 is provided.

45 The blade is carried, when in the holder 5, by the retainer 9, which may be made of cast steel or any like material. While the inside length of the retainer 9 and the length of the blade are of the same dimensions, the width of the retainer is narrowed so that the edges of the blade may project beyond the edges of the retainer. A substantially long stem 12 is centrally positioned on the inner face of the retainer and over this is adapted to fit the perforation 10 of the blade. As only one stem is used,

it would seem obvious that the blade would have angular lateral movement and to prevent this, the corners are provided with retaining lugs 13, which contact with the opposite short ends of the blade and fix the blade in a steady position. It will be seen that the retainer is provided at each end with recesses or cut-away portions 14 which admit of finger room when positioning the 60 blade or removing the same from the holder.

When the blade is positioned on the retainer 9 and fitted within the side lugs 13—13, the shield 8 is placed over the blade. This shield is substantially U-shaped and is 70 preferably formed of light spring metal. The sides of the shield are flared outwardly and the edges are preferably fluted as at 15, so as to provide guards for the edges of the blade and recesses for the material removed from the face during the operation of shaving. An opening 16 is centrally located in the top of the shield so that the stem 12 of the retainer may project therethrough. The handle 7 is provided with a screw-threaded bore 17, which is adapted to be screw-threaded over the head 18 of the stud 12. It will be noted that this head is relatively short and as only a portion of the bore 17 is screw-threaded, the handle can 85 be readily placed over the stem and a few turns will suffice to secure the parts together. As shown in Fig. 2, the lower portion 19 of the handle is narrowed so as to provide a shoulder 20. The part 19 is 90 adapted to be inserted in the opening 16 and the shoulder 20 will bear against the top of the shield; obviously, as the handle 7 is turned so as to tighten the parts, the shield will be under pressure and the result 95 will be, that the guard ends 15 will tend to separate, and reduce the cutting edges of the blade. Conversely, when it is desired to increase the cutting edges, the pressure on the shield is reduced. It will be seen by referring to Figs. 1 and 3 that the guards 15 are relatively longer than the sides of the shield and provide, thereby, ears 21; it will also be noted that one edge 22 of the lugs 13 is oblique and is provided with a notch 105 23. Now, the normal lateral distance between the ears 21 is less than the lateral distance between the remote edges of the lugs 13, and upon the shield being positioned on the blade, the action of the oblique edges 110 will be to spread the sides of the shield apart. This spreading increases until the

ears 21 reach the notches 23 in the lugs, whereupon the shield will be sprung into position and by virtue of the tension in the shield, the guards 15, bearing the blade 5 against the retaining member 9, will securely hold the blade in a relatively rigid manner.

It is obvious that those skilled in the art may vary the details of construction and arrangements of parts without departing from the spirit of my invention, and therefore I do not wish to be limited to such features except as may be required by the claim.

What is claimed as new is:

15 In a razor, the combination with a flat blade, of a blade retaining member hav-

ing oppositely disposed lugs positioned at the ends thereof, the said lugs having oblique sides provided with notches, and a resilient shield provided with laterally-extending guards having ears located at opposite ends, the said ears being adapted to be sprung over the oblique sides of the lugs and into the notches upon the shield being placed in contact with the blade. 20

In testimony whereof I affix my signature in presence of two witnesses.

GUS MAJOR KAISER.

Witnesses:

CHARLES LA RUE,
M. E. LAUGHLIN.
